APPARATUS FOR AND METHOD OF
COMBUSTION

Donald J. Mossart, Springfield, Pa., assignor of
one-half to Harold F. Hildreth, Springfield,
Mass.

Application April 19, 1935, Serial No. 17,162

14 Claims. (Cl. 110—44)

My invention relates to combustion apparatus and more particularly to stoker-fired furnaces of the small capacity type, for example, of the type suitable for use in heating dwellings, small houses, apartments, etc., which are commonly referred to as "domestic" stoker furnaces.

My invention has for one of its objects to provide apparatus of this general type which is of improved construction and arrangement of parts and which is capable of burning efficiently any one of a wide variety of solid fuels with practically no care by an attendant.

A further object is to provide a stoker furnace of the domestic type which is capable of burning automatically and efficiently any coal of the caking, non-caking, or free-burning types and without necessitating the care of an attendant to poke the fire or remove ash or clinker.

A further object is to provide a highly compact and conveniently arranged furnace unit whereby the fuel can be supplied thereto and ash removed therefrom with a minimum of labor.

A further object is to provide a furnace unit which is capable of being automatically regulated and which is adjustable throughout to meet widely varying load conditions.

A further object is to provide a stoker furnace suitable for domestic use wherein the ash is automatically or mechanically ejected into a suitable portable receptacle without the aid of an attendant regardless of the type of solid fuel burned.

A further object is to provide a furnace unit which is so constructed that the fire can be brought from a banked condition to a full load condition in a minimum of time, even though the furnace has been previously idle for a considerable length of time; thus providing a furnace which is admirably suited to meet widely varying conditions incident to heating buildings, homes, etc.

A further object is to provide a domestic stoker furnace wherein a fuel agitating member, for example, an air-emitting grate, moves transversely of the mouth of an upwardly-inclined fuel feeding duct and toward and away from a furnace wall to break up any caked fuel which might exist at the mouth of the fuel feeding duct following the resumption of furnace operation after a period of shut-down.

A further object is to provide an improved method of and an apparatus for burning fuel in a furnace wherein the fuel is fed into the furnace as a relatively narrow column, and the column is moved across the furnace chamber and

is broken up by pressure exerted thereon by the incoming fuel.

A still further object is to provide an improved method of and apparatus for burning fuel in a furnace whereby ash provides a support for a fuel column moving across the furnace chamber and the column is broken up by the pressure exerted by the incoming fuel.

These and other objects are effected by my invention, as will be apparent, from the following description and claims taken in connection with the accompanying drawings forming a part of this application, and in which:

Fig. 1 is a side elevational view showing my improved form of stoker fired furnace; 15

Fig. 2 is a vertical transverse sectional view taken on the line 2—2 of Fig. 1 showing certain parts of the operating mechanism in elevation for the purposes of clarity;

Fig. 3 is a longitudinal vertical sectional view taken on the line 3—3 of Fig. 2; 20

Fig. 4 is a fragmentary view illustrating in vertical longitudinal section, one form of speed reduction drive mechanism for my improved stoker; 25

Fig. 5 is a plan view of the supporting guide plate for the grate with the grate frame and grate bars in place thereon, the view being better understood by referring to the line 5—5 and directional arrows appearing on Fig. 3; 30

Fig. 6 is a view similar to Fig. 5, but showing the guide plate in plan with the grate frame and grate bars removed;

Fig. 7 is a longitudinal section taken on the line 7—7 of Fig. 6; 35

Fig. 8 is a plan view of the grate frame without the grate bars;

Fig. 9 is a plan view of the grate bars assembled without the frame;

Fig. 10 is a longitudinal vertical section of the grate frame, the view being taken on the line 10—10 of Fig. 8;

Fig. 11 is a detail view, showing in side elevation one of the grate bars;

Fig. 12 is a detail view, showing in side elevation another of the grate bars;

Fig. 13 is a horizontal sectional view taken on the line 13—13 of Fig. 1 and illustrating more in detail my improved form of air control;

Fig. 14 is a fragmentary vertical section similar to Fig. 3 showing the furnace in operation with the fuel bed therein, the view being somewhat diagrammatic in character;

Fig. 15 is a horizontal section taken on the line 15—15 of Fig. 14; 55

Fig. 16 is a fragmentary sectional view similar to Fig. 3 and illustrating a modified form of my invention; and

Fig. 17 is a longitudinal vertical sectional view 5 similar to Fig. 3 and illustrating a still further modification.

Referring now in detail to the construction illustrated, and particularly to the preferred embodiment of my invention which is shown in Figs. 10 1 to 14 inclusive, it will be observed that I have chosen to show my invention as applied to a heating furnace of a size suitable for domestic use. The furnace structure is indicated in general by the reference numeral 10 and includes a combustion chamber 11 defined by a front wall 12, a rear wall 13 and side-walls 14 and 15.

Solid fuel is supported during combustion by means of structure indicated generally by the reference numeral 16 and comprising a forwardly 20 and rearwardly reciprocating air-emitting grate 17, slidably supported by a stationary guide plate 18, the latter being in turn suitably supported by the furnace structure 10. Brackets 19 fixed to the side walls 14 and 15 form a part of the supporting means for the stationary guide plate 18.

That part of the grate 17 which is disposed adjacent the front wall 12 and midway between the side walls 14 and 15 is constructed in the form of a U so as to provide an opening or channel 30 20 through the grate. Solid fuel is fed upwardly through the opening or channel 20 from the upper open end of an inclined stationary duct 21. In the sense that the space indicated by the reference character 20 is void of structure, it may 35 be properly termed an opening; but, in the sense that this opening has substantial depth due to the height of its defining walls, it may also be properly referred to as a channel. The fuel is supplied to the lower end of the duct 21 from a suitable storage hopper 22. A rotating screw 23 40 within the duct 21 serves to feed the fuel from the hopper 22 longitudinally of the duct and upwardly through the opening 20 onto the grate 17.

In so far as certain aspects of my invention are 45 concerned, the screw 23 may be operated by any means suitable for imparting a rotary motion thereto, which means may be regulated to vary the amount of fuel fed to the combustion chamber. In the embodiment of my invention shown, 50 I have chosen to show an electric motor 24, operatively connected through a speed reducing mechanism 25 to a shaft 26 having a bevel gear 27 fixed to its outer end and meshing with a second bevel gear 28 fixed to the lower end of a shaft 29 on which the screw 23 is formed.

The mechanism 25 is shown in detail in Fig. 4 and is so constructed as to convert the constant rotary motion of the motor 24 into an intermittent rotary motion of the gear 27, which motion may 60 be varied at will. The mechanism 25 comprises a shaft 30 connected to the motor 24 by a pulley 31 and belt 32, and connected to a shaft 33 through a worm 34 and worm wheel 35. The shaft 33 is provided with a crank 36 which 65 drives the shaft 26 through a pawl and ratchet.

An arm 37 is loosely mounted at one end on the shaft 26 and is provided at its other and outer end with a swiveled member 38 which has an opening therethrough loosely receiving one end 70 of a connecting rod 39, the other end of the latter being connected to the crank 36. A compression spring 40 encircles the rod 39 and abuts at one end thereof a collar 41 fixed to the rod 39 and at its other end a collar 42 formed on the swiveled 75 member 38.

Motion of the crank 36 in a counter-clockwise direction from the position shown in Fig. 4 will result in a similar motion being imparted to the arm 37 through the spring 40, and this motion will continue until the crank 36 has traveled 90°. 5 After passing the 90° position, the arm 37 will be moved clockwise or to the right by means of the rod 39 and adjustable nut 43 on the rod 39. The clockwise motion of the arm 37 will continue until the crank 36 has traveled 270° from the position 10 shown, after which, forward or counter-clockwise motion will be imparted to the arm 37 through the spring 40, as previously explained.

A ratchet wheel 44 is fixed to the shaft 26 and is engaged by a pivoted pawl 45 carried by the 15 arm 37, and forward or counter-clockwise motion of the latter will cause the pawl to rotate the ratchet wheel 44 and shaft 26 an amount depending upon the point in the arc of forward movement of the arm 37 at which the pawl 45 20 engages the ratchet wheel. Rearward or clockwise movement of the arm 37 will result in the pawl 45 riding backward over the teeth of the ratchet 44. The ratchet wheel is prevented from moving backward or clockwise by a counter-weighted pivoted detent 46 carried by casing structure 47 enclosing the speed reducing mechanism 25.

The amount of motion imparted to the shaft 26 may be varied by varying the point at which 30 the pawl engages the ratchet wheel on the forward movement of the arm 37. To this end, an adjustable arcuate member 48 is provided which is carried by the outer end of an arm 49 loosely mounted on the shaft 26. The arcuate member 35 48 prevents the pawl from engaging the teeth of the ratchet wheel when the member 48 is positioned within the arc of movement of the pawl, the pawl riding upon and sliding across the face of the member 48. The position of the member 40 48 may be varied by an arm 50 fixed to the arm 49 and pivotally connected to the lower end of an operating rod 51, having a handle 52 at its upper end (see Fig. 1). The operating rod 51 may be held in any one of a number of desired positions 45 by the engagement of a projection 53 thereon in any one of a plurality of slots or notches 54 in a member 55 fixed to the hopper 22.

As stated, the fuel is fed longitudinally of the duct 21 and upwardly into the combustion chamber 11 and onto the grate 17 which extends laterally from the opening 20 therein. Air for combustion flows through the grate from a plenum chamber or wind box 56 beneath the grate, as will presently appear, and the fuel is burned on the 55 grate 17. The forward and rearward movement of the grate serves both to agitate the fuel bed supported thereby and also to move the bed rearwardly of the furnace. The solid products of combustion or ash gravitates through the fuel bed toward the grate and is moved rearwardly thereby and is ejected from the furnace through an opening 57 defined by a rearward extension of the guide plate 18 and the underside of the rear wall 13.

The method of feeding and burning the fuel just explained is known as underfeeding due to the fact the incoming green fuel is moved upwardly through the fuel bed. This type of feeding is admirably suited for burning high volatile coals, as 70 is well known. However, anthracite, prepared coke, and other low volatile fuels may also be burned satisfactorily in this manner. The underfeeding of fuel onto a domestic stoker grate is of course well known, but due to the arrangement 75

of the fuel feeding duct with respect to the walls of the combustion chamber, and to the construction of this duct and the construction and operation of the grate, my improved stoker is capable of burning without care by an attendant any type of solid fuel available, and particularly the highly caking or coking coals, which have not heretofore been burned satisfactorily without careful attendance and manual removal of clinker and ash from the fuel bed.

One of the principal novel features of my improved stoker is the means for breaking up or crushing any caked mass which might exist at the fuel inlet opening to the combustion chamber. As stated above, the grate 17 is provided with an opening or channel 20, the defining walls of which are arranged in the form of a U, and through which fuel is fed upwardly from the upper end of a stationary duct 21. The front wall 12 extends across the open side of the channel 20 and the closed side or base is defined by a surface 58 which extends upwardly and rearwardly and at the same angle of inclination as the duct 21. It will thus be seen that the channel 20 is in effect an extension or continuation of the duct 21, and the two form in effect a single continuous conduit through which fuel is fed from the hopper 22 onto the upper surface of the grate 17. The channel 20 forms an upper movable part of this conduit, and the duct 21 a lower stationary part. From an examination of Fig. 3, it will be observed that the upper end of the stationary duct 21 is provided by an opening or channel 59 through the guide plate 18. When the operation of the furnace is to be resumed after a shut down period, there usually exists within the opening or channel 20, due to the agglomerating properties of the fuel, a caked mass which must be broken up to permit the proper feed of fuel to the grate, and to effect the breaking up of this caked or agglomerated mass, I utilize the forward and rearward movement of the grate, which movement crushes or breaks up the caked mass between the surface 58 and the front wall 12. In fact, the part of the structure which provides the surface 58 can be likened unto a wedge which moves transversely of the caked or agglomerated mass within the opening or channel 20 and towards and away from the wall 12, and thereby acts to crush or break up the said mass so as to permit the flow of fuel from the hopper 22, through the duct 21, through the opening or channel 20, and onto the grate structure to thus promote combustion.

The action just described is, as stated, useful particularly when a caking coal is being burned and in starting up after a shut-down period. When the furnace is shut down, for example, by a thermostat in the house operating to open the switch of the motor, the fuel in the combustion chamber burns out and the inactive coal in and adjacent to the mouth of the fuel feeding conduit becomes caked. When the furnace is again started up the coaction between the moving inclined face 58 and the caked coal column and the front wall 12, serve to quickly break up the caked coal and in almost immediately obtaining active combustion adjacent to the mouth of the conduit. The intensely active fire then in the region of the mouth through which green coal enters the furnace greatly facilitates ignition of the incoming coal and results in quickly bringing the furnace and fuel bed to a condition of maximum rate of heat output.

Referring to the detail construction and operation of the fuel supporting structure 16 it will be

observed from an examination of Figs. 5 to 12 inclusive that the horizontal guide plate 18 comprises a main plate-like portion 60 which extends for the length and width of the combustion chamber and includes a rearward extension 61 over which the ash moves. The plate 18 also comprises wall structure defining the upwardly inclined opening 59 for the fuel, which was previously referred to and forms the upper part of the fuel feeding duct 21. A securing flange 62 is formed at the lower end of the opening 59 for the purpose of securing the flanged end 63 of the upper part of fuel feeding duct 21. The guide plate 18 is provided with spaced depending lugs 64 providing aligned journal bearing supports 65 for a 15 grate operating shaft 66 (see also Figs. 2 and 3). The main plate-like portion 60 is provided with a U-shaped opening 67 through which air for combustion flows from the wind box 56 to the grate.

The grate 17 comprises a grate frame 68 and a plurality of grate bars 69, 70 and 71. The grate frame 68 is shown in detail in Figs. 8 and 10 as consisting of wall structure defining an opening 72 and a U-shaped opening 73, the opening 72 being a part of the opening 20 previously referred to 25 and including the wedge shaped closed side 58, and the opening 73 surrounding the opening 72 and providing for the passage of the combustion supporting air to the grates. Spaced lugs 75 and 76 depend from the frame 68 at each side of the 30 opening 72 and are provided with aligned openings which receive a rod 77. Spaced links 78 and 79 are connected to the rod 77 at the outside of the lugs 75 and 76 and operatively connect the rod 77 and lugs 75 and 76 to the outer ends of 35 arms 80 and 81 respectively, the latter being fixed at their other ends to the grate operating shaft 66.

The shaft 66 extends outside of the furnace structure and has fixed thereto an operating arm 40 82 having a series of openings 83 formed therein (see Fig. 1). The shaft 66 and arm 82 are oscillated by a link 84 pivotally connected at one end to the arm 82 by a pin 85 fitting a selected one of the openings 83 and pivotally connected at the 45 other end to a crank 86 fixed to the extreme outer end 81 of the shaft 26, the latter being previously described as also operating the fuel feeding screw 23. Thus, the grate frame with the grate bars thereon is reciprocated forwardly and rearwardly 50 on the guide plate 18, and the amplitude of the reciprocations may be varied by changing the connection of the link 84 with the arm 82 to another of the remaining openings 83 in the arm 82.

As stated, the air-emitting grate surface is 55 formed by the grate bars 69, 70 and 71 supported by and fitting within the frame 68. The grate bars in assembled relation are shown in Figs. 5 and 9 and detail side elevations of grate bars 70 and 69 are shown in Figs. 11 and 12, respectively. 60 Grate bars 69 are shorter and extend between the inclined portion 58 of the frame and the rear side thereof. Right angle notches 90 at the front of the grate bars 69 and U-shaped notches 91 at the rear serve to position the grate bars in the 65 frame. The front upper face of each of the grate bars 69 is inclined, as indicated at 92, and forms a continuation of the face 58 of the frame. The grate bars 69 are provided with air passages 93 for conducting the combustion supporting air 70 to the fuel bed. Air may also pass through the joints between grates 69, and such is true of all 75 of the grate bars.

Grate bars 70 which flank the opening 20 are provided with notches 94, 95 and 96 which serve 75

to position them within the frame 68 and are also provided with air passages 97 in the side thereof adjacent the opening 20 for the purpose of directing the air into the fuel column within the opening 20. The passages 97 at their inner end communicate with spaces defined by the downwardly extending web portions of adjacent grate bars 70 and 71, and these spaces communicate in turn with the wind box 56.

10 Grate bars 71 are disposed in the frame 68 at the outside of the grate bars 70. The grates 71 are provided with notches (not shown) for positioning them within the frame 68 in the same manner as disclosed in connection with grate bars 69 and 70. Each of the grate bars 71 is provided with air passages 98 in the sides of the upper portion thereof which communicate with the spaces defined by the downwardly extending web portions of adjacent grate bars and thereby 15 serve as a means for conducting the air into the fuel bed.

15 All of the grate bars are provided with aligned openings 99 which also align with openings 100 provided in the sides of the frame 68. A rod 101 extends through the aligned openings 99 and 100 and serves to lock the grate bars in position in the frame 68.

20 In addition to providing an underfeeding action, the direction of movement of the fuel entering the combustion chamber performs another and important function which is one of the principal features of the present invention. When a furnace of the small type shown is operating with normal fuel bed conditions, as distinguished 25 from starting up after a shut-down period in the manner previously explained, the ignition and coking of the fuel for the most part takes place at points spaced from the mouth of the duct 21, and there is a pronounced tendency for the burning coked fuel to arch up and away from the 30 grate, with the result that the movement of the grate will have very little effect in breaking up the fuel bed. However, as will presently appear, due to my improved arrangement and manner of 35 fuel feed and the relative size and position of the parts, the fuel bed on my grate is maintained in a broken-up or porous condition.

40 It will be observed from an examination of Figs. 3, 14 and 15 that fuel entering the combustion chamber moves in the general direction of the rear wall 13. When the furnace has operated for a short time and built up a normal fuel bed, the entering fuel column maintains its column-like formation throughout the length of the furnace, with the rear end of the column adjacent 45 the rear wall. The force exerted by the screw 23 on the column of entering fuel will be transmitted thereby to the rear wall, and as a result the fuel in the column will be compressed to such an extent that it will break up and spread laterally onto the grate and the motion of the latter will aid in keeping the fuel bed broken up. In other words, due to the direction of fuel feed and the position of the rear wall, the entering fuel 50 column breaks itself up and thereby provides for the flow of air through the fuel bed and the burning out of the combustible therein. As a fuel column is broken up by compression in the manner just explained, and the burning fuel spreads laterally onto the grate, the constantly 55 incoming stream of fresh fuel maintains the columnlike formation across the furnace.

60 In Figs. 14 and 15 the fuel column is indicated at A. If the fuel is a caking type, the volatile constituents will be driven off as it moves toward

the rear wall and the tarry substances in the fuel will exude and tend to bind the fuel together and thus prevent the necessary flow of air therethrough. The compression action just explained will cause the fuel bed to break up and the broken particles, which by this time will be practically solid carbon or coke, will spread laterally onto the sides of the grate. The coke particles are indicated at B. The solid non-combustibles gravitate to the lower portion of the fuel bed as 10 ash and clinker which is fed out through the opening 57 by the reciprocating action of the grate. It is to be noted at this point that the movement of the grate also aids in breaking up the fuel bed. The ash is indicated at C and the 15 clinker at D. In this connection it is to be noted that the ash piles up at the rear of the furnace and provides an inclined support for the rear end of the fuel column. This is important, as it maintains the direction of movement of the column A 20 toward the rear wall so that the latter will be broken up by compression, as explained above.

25 Another and important advantage is attained from maintaining a bed of ash beneath the rear portions of the fuel bed when certain types of fuel are burned, for example, bituminous coals. This advantage is that the ash offers a substantial resistance to the flow of air through the rear portions of the bed and thereby assures adequate 30 flow of air through the front portions of the fuel bed where the resistance to air flow is normally and relatively higher due to the greater degree of coking action taking place at the front. By varying the amount of accumulated ash, the resistance, to air flow may be changed to suit the 35 particular type of fuel being burned.

40 Another feature of my invention is the fact that the mouth or inlet of the fuel-feeding conduit being relatively narrow with respect to the width of the grate, space is provided into which the 45 broken up particles are permitted to spread laterally and burn.

45 The rate of ash discharge must be regulated so as to maintain the desired support for the fuel column, as just explained, and also so as to 50 seal the outlet opening 57 against the harmful infiltration of air therethrough into the combustion chamber. According to my invention, I provide for a regulated rate of ash discharge and for the breaking up of any clinker formations 55 therein. To this end, I provide a plate 105 which is positioned to partially close the opening 57 and is reciprocated in a vertical plane so as to shear or break up the clinker. The plate 105 is provided with teeth 106 on its forward surface which feed the ash and clinker downwardly toward the opening and also crush and break them up. The lower edge of the plate will shear any clinker as the latter is moved out through the opening 57 by the reciprocating grate 17.

60 The plate 105 is slidably mounted between the rear face of the rear wall 13 and a pair of guide strips 107 secured to the side walls 14 and 15. The plate 105 is supported and reciprocated by pins 108 on the outer ends of arms 109 and 65 engaging between spaced projections 110 fixed to the rear face of the plate. The arms 109 are fixed to an operating shaft 111 which extends out of the furnace as shown in Fig. 1 and is provided with an arm 112 fixed thereto and having a retractable latch 113 at its outer end which may be caused to engage any one of a series of notches 114 formed on the outer arcuate surface of an arm 115. The arm 115 is loosely mounted on the shaft 111 and is provided with a depending por- 70 75

tion 116 which is connected to one end of a link 117, the other end of the link 117 being connected by a pin 118 with one of the openings 83 in the arm 82.

5 Thus, with the latch 113 engaging a notch 114, oscillatory motion of the arm 82 will be transmitted through the link 117, arm 115, arm 112, shaft 111, and arms 109 to the plate 105. The amplitude of reciprocation of the plate depends 10 upon the particular opening 83 within which the pin 118 is placed. Thus, by changing the pin to another opening the amplitude may be varied to suit different operating conditions. The size of the ash discharge opening 57 may be varied 15 by varying the position of the plate 105. This latter is effected through the retractible latch 113 and the series of notches 114.

The ash ejected through the opening 57 falls 20 into a suitable receptacle 120, which may be re- placed by another receptacle when filled. This procedure will avoid the shoveling of ash in the basement, which causes objectionable dust.

Air for combustion is supplied to the wind box by a fan 121 driven directly by the motor 24 25 (see Figs. 1, 2, 3 and 13). The fan 121 comprises a rotor 122 connected to the shaft of the motor 24, a casing 123 surrounding the rotor and having an inlet communicating with a duct 124 and an outlet communicating with the wind box 56.

30 In order to provide an adequate and even flow of air through the fuel bed at all times, I provide an automatic control which operates to vary the air supply in accordance with the resistance offered to the flow of air by the fuel bed. If the 35 fuel bed is relatively porous or thin the pressure of air in the wind box is reduced by my control so that only the desired amount will flow through the fuel bed. If, on the other hand, the fuel bed is thick or if it is caked or agglomerated to 40 any extent the pressure of the air in the wind box is increased by my control to an amount sufficient to force the desired amounts of air through the fuel bed.

I accomplish these very desirable results by 45 providing a fan of high enough capacity to produce a pressure in the wind box sufficient to force adequate amounts of air through the fuel bed when the resistance offered thereby to the flow is the greatest that can be expected, and then by regulating the amount of air supplied to the inlet side of the fan in accordance with the rate of flow of the air to the fan.

The flow of air to the inlet of the fan is regulated by a damper 125 in the duct 124, and the damper is automatically controlled by the rate of air-flow through the duct 124. The damper 125 is connected by a linkage 126 with a flapper 127 pivotally mounted along one edge, as indicated at 128, to a side of an extension 129, which 50 latter communicates with the duct 124 at the inlet side of the damper. The flapper 127 is so arranged that the weight thereof tends to move it about its pivotal support and open the damper 125. One side of the flapper 127 is exposed to 55 the pressure of the air in the duct and the other side is exposed to the atmosphere. The air inlet to the duct 124 is indicated 130 as being an orifice, the size of which may be varied by a slide damper 131. As the entering air flows 60 through the orifice, the pressure of the air within the duct is less than that of the atmosphere and the difference in pressure will depend on the size of the orifice and rate of air flow through the orifice. With one side of the flapper exposed to 65 the air pressure in the duct and the other side to

the atmosphere, the flapper will move against its own weight to close the damper 125 until the force created by the differences in pressure and that resulting from the weight of the damper are balanced. If the rate of air flow varies due to changes in the resistance offered by the fuel bed to the flow of air therethrough, the difference in pressure between that of the duct and that of the atmosphere will change and the flapper 127 will move to a new position of equilibrium 10 and move the damper 125 to admit more air or less air, as the case may be. Adjustments of the slide damper 131 to vary the orifice 130 will change the amount of air flowing through the fuel bed to any desired amount. The slide 15 damper 131 may be regulated by a control lever 132 operating through a link 133, lever 134 and link 135.

The construction thus far described is highly 20 compact and conveniently arranged and may be enclosed in a suitable and attractive casing. Due to the inclined coal feeding duct 21 and the height of the fuel supporting surface 16, the coal feeding hopper 22 may be placed relatively 25 low so as to require the minimum of labor in filling, and an ash receptacle 120 may be provided which may be quickly and easily removed and another placed in its stead. I have found that in operation, no attention is required to the fire. The furnace may be operated automatical- 30 ly by a room thermostat or by other suitable devices, and all that is required is to keep fuel in the hopper and replace the ash receptacle. The thermostat may be connected to the control switch of the motor 24 which operates both 35 the fuel feeding screw and the fan. No need is had for poking the fire or manual removal of clinker, even though low grade or highly coking coals are burned. The coaction of the arrangement of the duct 21, the front wall 12, and 40 the inclined face 58 of the grate serve to quickly bring the fire to normal after a period of shut down. The arrangement of the duct 21 with respect to the rear wall 13 and the width of the 45 grate 17 results in the fuel bed being maintained in a porous condition during normal operation. The latter is aided by the position and manner 50 of ash discharge. The various adjustments are for the purpose of providing the best operation for the type of fuel burned and for the desired 55 heat output or capacity of the furnace.

In Fig. 16, I have illustrated a possible modification of my invention. The fuel feeding duct 21a is illustrated as being substantially vertical 55 at its inlet end. The desirable feature of shearing or breaking up the entering fuel is attained by the grate 17a having the opening 20a defined by U-shaped walls and moving transversely of the mouth of the duct 21a to crush the fuel against the front wall. The same type of ash 60 discharge is provided as in the previously described modification.

In Fig. 17, I have illustrated a further modification of the fuel feeding duct. The duct is indicated at 21b and the mouth thereof is ar- 65 ranged more horizontally than the duct 21 in the first embodiment described and thus provides a more positive crushing action of the fuel feeding column against the rear wall 13b. However, the breaking up of the column at 70 the mouth of the duct is not positive like that of the previously described design because the grate is not provided with an opening defined by U-shaped walls and the grate does not move transversely across the mouth of the fuel feed- 75

ing duct. However, in Fig. 17, a breaking up action will be had at the mouth of the duct 21b due to the upward wedging action of the inclined front face 140 of the moving grate.

5 While I have shown my invention in one preferred embodiment and have suggested two modifications, it will be obvious to those skilled in the art that it is not so limited but is susceptible of various other changes and modifications without departing from the spirit thereof, and I desire, therefore, that only such limitations shall be placed thereupon as are imposed by the prior art or as are specifically set forth in the appended claims.

15 I claim:—

1. In combustion apparatus, the combination of means defining a combustion chamber including front and rear upwardly extending wall portions, means for feeding solid fuel into the combustion chamber at points adjacent the front wall portion and in a direction extending upwardly and toward the rear wall portion so that the fuel in entering moves in a column extending across the combustion chamber from the 25 front wall portion towards the rear wall portion whereby the column of fuel breaks up due to the crushing action against the rear wall portion, and a member movable transversely across the fuel column as it enters the combustion chamber and toward and away from the front wall portion so as to crush therebetween any caked mass which may exist in the space where the fuel column enters the combustion chamber.

2. In combustion apparatus, the combination 35 of means defining a combustion chamber including front and rear upwardly-extending wall portions, means for feeding solid fuel into the combustion chamber including a duct having the end thereof adjacent the combustion chamber 40 upwardly inclined toward the rear wall portion and entering the combustion chamber at points adjacent the front wall portion so that the fuel column is crushed against the rear wall portion and thereby broken up, and a wedge-shaped member movable transversely of the mouth of the duct and towards and away from the front wall portion so as to break up any caked mass which may exist at the mouth of the duct.

3. In combustion apparatus, the combination 50 of means defining a combustion chamber and including upwardly extending front and rear wall portions; means providing a substantially flat fuel-supporting surface extending across the lower end of the combustion chamber; means for 55 feeding fuel onto the fuel-supporting surface at points adjacent the front wall portion and in such a manner that the fuel moves across the surface in a column of less width than the said surface and in the direction of the rear wall portion and so that the column strikes the rear wall portion whereby the column is forced against said rear wall portion and is constantly broken up and the burning fuel spread laterally onto the said surface; said last-named means comprising an upwardly and rearwardly inclined conduit having the combustion chamber end thereof of less width than the said fuel supporting surface and extending into the combustion chamber adjacent the front wall and at the level of the fuel supporting surface and opening in the direction of the rear wall, and means outside of said chamber for positively pushing solid fuel through said conduit and onto said fuel supporting surface; means providing an ash discharge orifice beneath the rear wall

portion; and means providing for the reciprocation of at least a portion of the fuel-supporting surface towards and away from the ash discharge orifice for feeding the ash through said orifice.

4. In a combustion apparatus, the combination of means defining a combustion chamber including an upwardly extending rear wall portion; means providing a substantially flat fuel-supporting surface extending across the lower end of the combustion chamber and including an air-emitting grate structure movable toward and away from the rear wall portion; said grate structure having a channel extending therethrough at a point remote from the rear wall portion; said channel being of substantially less width than the grate structure, and being inclined upwardly and toward the rear wall portion; and means for forcing fuel through the channel and onto said grate structure so that the fuel moves in a column across the grate structure and strikes the rear wall portion and is broken up by compression against said rear wall portion and spread laterally onto said grate structure.

5. In combustion apparatus, the combination of means defining a combustion chamber including front and rear upwardly extending wall portions; a fuel-supporting grate structure extending across the lower part of said combustion chamber; means for positively forcing solid fuel into the combustion chamber at a point adjacent the front wall portion and in a direction extending toward the rear wall portion so that the fuel moves across the grate structure in a column of substantially less width than the grate structure and strikes the rear wall portion, whereby the column is continually broken up by compression against said rear wall portion and the broken particles are spread laterally onto the grate structure; said grate structure including means for crushing a portion of the fuel column against the front wall portion where said column enters said combustion chamber so as to accelerate ignition and promote active combustion of the column upon resumption of fuel feed following a period of inactivity; and means for reciprocating said grate structure toward and from said front wall portion.

6. In combustion apparatus, the combination 50 of front, rear and side wall parts defining a combustion chamber; a substantially flat grate extending across the lower part of said combustion chamber; a fuel-feeding conduit having an open outlet end communicating with the combustion chamber at a point adjacent the front wall part and between the side wall parts at the level of the grate and being of substantially less width than the distance between the side wall parts; the open outlet end of said conduit being arranged to discharge solid fuel towards said rear wall part; means for positively forcing solid fuel through said conduit and into said combustion chamber so that the fuel moves across said grate in a column of substantially less width than the grate and strikes the rear wall part, whereby the column is continually broken up by compression against the rear wall part and the broken particles are spread laterally onto the grate; means providing for reciprocatory movement of the grate towards and away from the rear wall part so as to feed the resulting ash in the same general direction as the direction of movement of the fuel column; and means adjacent the rear

wall for permitting the removal of ash from the combustion chamber.

7. In combustion apparatus, the combination of front, rear and side wall parts defining a combustion chamber; a substantially flat grate extending across the lower part of said combustion chamber; a fuel-feeding conduit having an open outlet end communicating with the combustion chamber at a point adjacent the front wall part 5 and between the side wall parts at the level of the grate, and being of substantially less width than the distance between the side wall parts; the open outlet end of said conduit being arranged to discharge solid fuel towards said rear wall parts; means for positively forcing solid fuel through said conduit and into said combustion chamber so that the fuel moves across said grate 10 in a column of substantially less width than the grate and strikes the rear wall part, whereby the column is continually broken up by compression 15 against the rear wall part and the broken particles are spread laterally onto the grate; means providing for reciprocatory movement of the grate towards and away from the rear wall part 20 so as to feed the resulting ash in the same general direction as the direction of movement of the fuel column; and means adjacent the rear wall for permitting the removal of ash from the combustion chamber; said grate including means 25 for crushing a portion of the fuel column against the front wall part where said column enters said combustion chamber so as to accelerate ignition and promote active combustion of the column upon resumption of fuel feed following a period 30 of inactivity.

8. In combustion apparatus, the combination of front, rear, and side wall parts defining a combustion chamber; a substantially flat grate extending across the lower part of said combustion chamber; a fuel-feeding conduit having an open outlet end communicating with the combustion chamber at a point adjacent the front wall part and between the said wall parts at the level of the grate, and being of substantially less width 40 than the distance between the side wall parts; the open outlet end of said conduit being arranged to discharge solid fuel towards said rear wall part; means for positively forcing solid fuel through said conduit and into said combustion chamber so that the fuel moves across said grate 45 in a column of substantially less width than the grate and strikes the rear wall part, whereby the column is continually broken up by compression against the rear wall part and the broken particles are spread laterally onto the grate; means providing for reciprocatory movement of the grate towards and away from the rear wall part 50 so as to feed the resulting ash in the same general direction as the direction of movement of the fuel column; means adjacent the rear wall for permitting the removal of ash from the combustion chamber; and means for regulating the rate of ash discharge with respect to the rate of fuel feed so as to maintain a supporting bed of 55 ash beneath that part of the column which is closer to the rear wall part and assure the engagement between the end of said column and said rear wall part.

70 9. In combustion apparatus, the combination of means defining a combustion chamber and including front, side and rear walls; a fuel feeding conduit extending into said combustion chamber at a point adjacent the central portion only 75 of the front wall and positioned to discharge

fuel in a single general direction upwardly and toward the rear wall; a fuel supporting grate extending laterally and rearwardly from the upper open end of said conduit and toward said side walls and rear wall respectively, said grate having an opening through its front central portion coextensive with and registering with the upper open end of said conduit, the walls defining the sides of the opening in the grate being spaced from the side walls of the combustion chamber to 10 form at each side of said opening a lateral fuel supporting surface of substantial width; and means for positively forcing solid fuel longitudinally of the conduit through said opening in said grate structure, into said combustion chamber 15 and upwardly and rearwardly toward said rear wall, so that the fuel is forced into the combustion chamber in the form of a narrow column, the inner end of which is forced into contact with the rear wall to thereby break up the column and spread portions thereof into the said lateral fuel supporting surface at each side of said column. 20

10. Apparatus according to claim 9 wherein means are provided for discharging the resulting ash from the combustion chamber and wherein such means are adjustable to vary the rate of ash discharge so as to maintain within the combustion chamber adjacent the rear wall thereof, a supporting bed of ash beneath the inner end of the fuel column. 25

11. In combustion apparatus, the combination of means defining a combustion chamber and including front, side and rear walls; a grate arranged across the lower part of said combustion chamber and having a fuel feeding opening extending therethrough at a point adjacent the front wall and spaced from the side and rear walls with the defining walls of said opening arranged in the form of a U and with the grate so positioned that the front wall of the combustion 40 chamber extends across the open side of said opening, the walls of said grate which define the sides of said opening being spaced from the side walls of the combustion chamber to form at each side of said opening a lateral fuel supporting surface of substantial width; a stationary duct having an open outlet end arranged below said grate and registering with said opening; means for positively forcing solid fuel through said duct and onto said grate through said opening and in a 45 direction extending toward the rear wall of said combustion chamber, so that fuel is forced into the combustion chamber in the form of a narrow column, the inner end of which is forced into contact with the rear wall to thereby break up the column to spread portions thereof onto the said lateral fuel supporting surfaces at each side of said column; and means providing for reciprocatory movement toward and away from said front wall of at least that part of said grate 50 which defines said opening so that the part of the grate which is opposite said front wall will crush against said front wall any coked mass of fuel which may exist in the space where the fuel column enters said combustion chamber. 55

12. Apparatus according to claim 11 wherein the portion of the grate which is opposite said front wall is inclined upwardly and toward the rear wall, and wherein the stationary duct discharges upwardly and toward the rear wall so that the narrow column of fuel progresses from the front to the rear of the combustion chamber in an upwardly and rearwardly inclined direction. 70

13. The method of burning a coking coal comprising the steps of producing a burning fuel bed; 75

positively and continuously forcing a narrow stream of coking coal through the fuel bed intermediate the sides of said fuel bed, whereby the outer surface of said stream is coked by the heat 5 of said fuel bed; arresting the movement of the inner end of said stream; utilizing the force exerted on the narrow stream by the pressure of the incoming fuel to set up within said stream internal pressure sufficient to break off and spread 10 laterally the coked outer surface of said stream as the same is formed and to thus expose the surface of the inner raw fuel of said stream to coking action; and continuing the burning of the coked particles continuously broken off from the 15 surface of said stream as such particles spread laterally into said fuel bed.

14. The method of burning a coking coal comprising the steps of producing a burning fuel bed; positively and continuously forcing a narrow

stream of coking coal through the fuel bed intermediate the sides of said fuel bed, whereby the outer surface of said stream is coked by the heat of said fuel bed; arresting the movement of the inner end of said stream; maintaining a supporting bed of ash beneath the inner end of said stream; utilizing the force exerted on the narrow stream by the pressure of the incoming fuel to set up within said stream internal pressure sufficient to break off and spread laterally the coked outer surface of said stream as the same is formed and to thus expose the surface of the inner raw fuel of said stream to coking action; and continuing the burning of the coked particles continuously broken off from the surface of said 15 stream as such particles spread laterally into said fuel bed.

DONALD J. MOSSHART.
